UNITED STATES PATENT OFFICE.

CLIO L. WOOD, OF COALINGA, CALIFORNIA.

PUMP-ANCHOR.

1,108,537.

Specification of Letters Patent. Patented Aug. 25, 1914.

Application filed October 20, 1913. Serial No. 796,358.

To all whom it may concern:

Be it known that I, CLIO L. Wood, a citizen of the United States of America, of Coalinga, county of Fresno, State of California, have invented a new and useful Improvement in Pump-Anchors, of which the following is a description, reference being had to the accompanying drawings.

This device is especially adapted for use 10 in oil wells. In most oil wells the pump cylinder is attached to the bottom of the suction pipe which extends hundreds and often several thousand feet downward in the well. This long line of pump pipe was formerly 15 suspended from the top of the well, but the great weight and jar of the pump caused the pipe to part. In falling the lower part of the pipe would frequently bend and twist. In any event upon the parting of the pipe 20 it is necessary to take all the pipe and pump out of the well and replace it, causing great expense and loss of production. To avoid such parting of the pump line, anchors have been devised to support the pipe 25 from below. These anchors furnish support at any desired location by jaw toothed plates wedged against the side of the well casing. In the anchors heretofore devised these plates and wedges are operated by 30 a spring device and cannot be re-set without removing the whole line of pipe and the re-setting of the spring device. In many wells such operation represents a full day's labor. By means of the device which I 35 have invented and for which I now make application for Letters Patent, the anchor can be set, released and re-set at any depth in the well, at once, in a moment of time.

Referring to the drawings, Figure 1 is a 40 cross-section view of the anchor with the jaw plates set against the sides of the casing; Fig. 2 and Fig. 3 give detail views of the operating parts. Fig. 4 is a detail sectional view taken on the line 4—4 of Fig. 2.

45 1 is the well casing, 2 the pump pipe or suction pipe.

The pump cylinder is not shown but would ordinarily be located just above the part shown in the drawing.

50 3 is a notched and slotted piece of pipe within the pump pipe fitting snug up and attached to it by the pin 4.

5 is the swedge shaped body upon which

the jaw plates 9 and 9' are spread against the inside of the casing. These plates are 55 slightly convexed to fit the inside of the well casing and are provided with sharp teeth on the convex surface. 5 is united to the pump pipe by the coupling 6, by means of the screw threads 7. 60

8 is a groove in 5 to permit passage of oil or water.

10 is a dove tail groove in each jaw plate which slides upon the dove tail guide 11 on the swedge 5. This swedge also has a 65 shoulder, 11' on each side to prevent the jaws slipping up too high.

12 and 12' are pins which extend loosely into the jaw plates from the collar 14 which loosely encircles the main operating rod. 70

13 represents slots in 5 in which the pins move up and down. This rod is turned down to a small neck 16 at the point where the collar encircles it thus making a shoulder 17, on each side of the collar to hold it in 75 place. This is done by making this rod in two pieces 15 and 15' and uniting them by screw threads at the point where the collar encircles it.

The pieces 22 and 22' are flat springs 80 adjusted to press firmly against the inside of the casing thereby making sufficient resistance to trip the operating device. 21 and 21' are the arms which hold the flat springs. 85

23', 23'', 23''' and 23'''' are screw nuts which hold the springs in place and 24 and 24' are nuts which adjust the tension of the springs against the casing. The pin 26 also helps hold the upper arm in place. 90

The pin 25 passes through the upper part of the operating rod, works up and down in the groove 27' and into and out of the notch 27. This groove and notch are one continuous opening. The catching of this 95 pin in the notch 27 or its freedom in the groove 27' governs and controls the operation of the device.

In operation the swedge 5 and the jaw plates 9 and 9' form the anchor and do the 100 actual work. When the plates are raised upon the swedge the anchor is fastened to the side of the casing. When the plates are lowered with relation to the swedge they are freed from the casing and the dove tail 105 guides pull them from the casing. The ob-

ject of my device is to raise and lower the jaw plates with relation to the swedge, at pleasure.

The jaw plates are raised and lowered by 5 the pins 12 and 12' carried in the collar 14 which is loose upon the rod 15—15' and does not turn with it but is, because of the neck 16 and shoulders 17, raised and lowered with the rod. I speak of the rod being 10 raised and lowered but for the purpose of description only, for in operation, the rod, the pins upon it, and the jaw plates remain stationary (or relatively so) held so by the resistance furnished by the spring 15 plates 22 and 22' pressing against the casing. The only part of the device which extends to the top of the well, and by which the device can be controlled by the operator is the pump pipe to which the swedge 5 and 20 the grooved part 3 are attached.

When the pump pipe is raised the main operating rod 15—15' and the jaw plates governed by it do not move until the bottom of the groove 27' has reached the pin 25. From there on the whole apparatus rises together. Suppose it is raised to the point desired and then lowered without giving the pipe a turn, then the pin 25 immediately rises in the groove 27' and the 30 rod 15—15' carries the jaw plates upward and outward against the casing, or rather the swedge 5 presses down and crowds the plates out firmly against the casing, thereby anchoring the pump line to the casing of 35 the well. But suppose that just before lowering the pipe, it is given a quarter turn, thereby placing the notch 27 over the pin 25, then when the pipe is lowered the rod 15—15' together with the jaw plates and 40 the resisting spring plates 22—22' immediately move off with the swedge 5 and the swedge has no opportunity to crowd the plates out against the casing. When the desired depth has been reached a quarter turn 45 of the pipe from the top of the ground brings the groove 27' over the pin 25 again and the swedge immediately presses down and outward against the jaw plates crowding them against the casing.

50 What I desire to secure by Letters Patent, is:

1. In a pump anchor having a swedge shaped body attached to the suction pipe of a pump, and slideable plates upon the faces 55 of the swedge, means for sliding the plates upon the swedge shaped body as follows; a rod passing freely vertically through the center of the swedge shaped body, a projection on the side of the upper end of said 60 rod, means for catching and releasing the projecting portion of said rod, a collar around the middle part of the rod, free therefrom so the rod may rotate without moving the collar, means upon the rod for raising

and lowering said collar with said rod, pins 65 extending from the collar outward into the slideable plates and carrying the plates upon them, a well casing a friction device fixed upon the lower end of said rod, adjusted to press against the side of a well casing, in 70 combination substantially as shown.

2. A pump suction pipe and pump anchor comprising a swedge shaped body adapted to be attached to the pump suction pipe, said swedge shaped body having a plurality of 75 plane faces each such face being provided with a dove-tail ridge, and toothed convex plates with dovetail grooves slideable upon the faces of the swedge, means for sliding said plates upon the faces of said swedge 80 as follows: a rod extending vertically through the anchor, means extending from said rod into said plates to raise and lower them as the rod is raised and lowered, flat springs on arms attached to the lower end 85 of the rod, pressing against the casing of the well, a slot and groove device near the top of the rod workable in connection with a pin through the rod whereby the rod is raised and lowered with the suction pipe 90 and swedge shaped body at the will of the operator.

3. A pump suction pipe and pump anchor comprising a swedge shaped body adapted to be attached to the pump suction pipe, said 95 swedge shaped body having a plurality of plane faces each such face being provided with a dove-tail ridge, toothed convex plates with dovetail grooves slideable upon the dovetail faces of the swedge, a rod passing 100 vertically through the center of the swedge shaped body, a collar around said rod carrying pins which extend into and carry the said plates, a spring friction device fixed upon the lower end of said rod, a suction 105 pipe provided with a continuous groove and slot, the pump suction pipe being provided with a bayonet slot, a pin extending laterally from the top of said rod and adapted to move vertically and to rotate laterally 110 within the portions of the bayonet slot in combination substantially as shown.

4. In a pump suction pipe and a pump anchor having a swedge shaped body adapted to be attached to the pump suction pipe, 115 said swedge shaped body having a plurality of plane faces, slideable plates upon the faces of the swedge, means for sliding the swedge upon the plates as follows: a rod passing freely vertically through the center of the 120 swedge, arms extending from said rod into said plates and carrying them up and down with the rod, a well casing a friction device upon the lower end of the rod adjusted to press lightly against the side of the well 125 casing, the pump suction pipe being provided with a vertical groove and a horizontal groove opening into the lower end

of the vertical groove, a pin extending laterally from the top of said rod and adapted to slide in the vertical groove and to rotate in the horizontal groove, in combination substantially as shown.

5 In witness whereof, I have hereunto sub-

scribed my name in the presence of two witnesses.

CLIO L. WOOD.
